UNITED STATES PATENT OFFICE.

ARTHUR R. BULLOCK, OF CLEVELAND, OHIO.

CURRENT-CONVERTING DEVICE.

1,223,473.

Specification of Letters Patent. Patented Apr. 24, 1917.

Application filed December 22, 1913, Serial No. 808,116. Renewed September 20, 1916. Serial No. 121,312.

To all whom it may concern:

Be it known that I, ARTHUR R. BULLOCK, a citizen of the United States, residing at Cleveland, in the county of Cuyahoga and 5 State of Ohio, have invented a certain new and useful Improvement in Current-Converting Devices, of which the following is a full, clear, and exact description.

This invention relates to a means for 10 equalizing the flow of current from a plurality of terminals of a circuit in which a pulsating current is flowing.

Generally speaking, the invention comprises the elements and combinations thereof 15 set forth in the accompanying claims.

Reference should be had to the accompanying drawings forming a part of this specification, in which Figure 1 is a top plan view of a current converting device. Fig. 2 20 is a section on the line A—B looking in the direction of the arrow C. Fig. 3 is a section on the line A—B looking in the direction of the arrow A; Fig. 4 is a diagram of the electrical connections; Fig. 5 is a 25 diagram of the electrical connections where a plurality of brushes on the commutator are used.

In many instances it is necessary or desirable to split up a circuit carrying a pulsating current, unidirectional or alternating, 30 into a plurality of circuits connected in parallel and to cause each of the circuits thus formed to carry an equal amount of current. This is not an easy matter, particularly where all or part of these parallel 35 arranged circuits may be made and broken at times.

I have found, if such parallel arranged circuits each have a coil in series and all 40 these coils be arranged upon a single iron core so shaped that the magnetic circuit is closed, that the current, flowing in each circuit is equal if the wire resistance of the circuit is equal.

45 As one example or instance of the application I would mention converting devices of such types as the vibratory rectifiers or rotating segment rectifiers, which connect the sides of an A—C circuit alternately with 50 the sides of a D—C circuit, all produce from a single phase alternating current, a direct current which is highly pulsating in character.

If such devices be provided with a plurality of positive terminals and negative 55 terminals, it is difficult, if not impossible, to obtain an equal flow of current from each of the terminals. It usually happens that more current flows from one terminal than from another, due to the variation in brush 60 contact and vibrator button contact. This is disadvantageous in many instances, particularly in converting the devices of the rotating segment type which have heretofore been mentioned, for such devices, the 65 current is usually collected by means of rotating brushes, bearing on the segments, and it is necessary to use a plurality of brushes with such types of devices so as to increase the current carrying capacity of the machine. 70 It is quite essential that the current equally distribute itself between the brushes, otherwise a single brush may be forced to carry a greater amount of current than it should, and produce a sparking or perhaps 75 the more dangerous arcing between the brush and commutator.

I have disclosed my invention in connection with a converting device of the rotating segment type. However, the invention itself is usable in other connections, and I do not limit myself to the use of the invention in connection with the machine of the disclosure.

In Fig. 1, a shaft 1 is supported in bearings 2 and 3, which may be suitably mounted upon any standard or base. The shaft supports a rotating body 4, which is provided with conducting portions or members represented at 5, 6, 7 and 8 shown in Fig. 2. 85 These conducting portions are shown as segmented, merely because in commercial construction it is more practical to make them in this fashion. However, as far as the electrical principle underlying is concerned, 90 each of these sections or portions might be a solid block of conducting material.

Adjacent the body 4 and mounted upon the shaft 1, are collector rings 9 and 10 which are insulated from the shaft and are 100 insulated from each other by an insulating body 11.

On the shaft 1 there is also supported a rotating body 12, this body being provided with conducting portions 13, 14, 15 and 16. 105

The conducting portions 5 and 13 are elec-

trically connected, as are the conducting portions 6, 7 and 8 with the conducting portions 14, 15 and 16 respectively. Also the conducting portions 5 and 7 are connected together, and the conducting portions 6 and 8, and also the conducting portions 13 and 15 electrically connect, as is also the case with the conducting portions 14 and 16. The rings 9 and 10 are respectively connected with the conducting segments 5, 7 and 6, 8.

A suitable support represented at 17 in Fig. 1 supports a ring 18 from which extend brush supports, one of which is indicated at 19 in Fig. 1. These brush supports carry the usual brush holders, which bear respectively upon rings 9 and 10 and upon the conducting portions upon the body 4. As shown, four brushes are used which are so placed that they will simultaneously bear upon the same portions of each of the conducting portions upon the body 4.

A support 20 has mounted thereon rings 21 from which extend brush supports 22, there being four of such brush supports, and these supports carry the brush holders, there being four brushes, or four sets of brushes, as will be later explained, which bear upon the conducting portions of the body 12, as shown in Fig. 3.

The brushes 23 and 24 are electrically connected, and brushes 25 and 26 are electrically connected with each other and also connected in series with the brushes 24 and 23. Brushes 27 and 28 are electrically connected together, as well as brushes 29 and 30, and these last mentioned brushes are in turn connected with the brushes 27 and 28. This will clearly be seen by reference to Fig. 4.

The live portions or segments 13, 14, 15, 16, are so related to the segments 5, 6, 7 and 8 that the break in the circuit occurs between segments 13, 14, 15 and 16 and the brushes with which they coöperate. That is brushes 23, 27, 25 and 29 break contact with their segments just before brushes 24, 28, 26 and 30 break connection with their segments.

In series with the brushes 23 and 24 is a reactance coil which is generally represented at 31. In series with portions 25 and 26, there is also a reactance coil 32, and these coils are in parallel with the conductor 33 which forms a part of the external D C circuit. These coils 31, 32 are wound upon a common core 31^a which is constructed to have a closed magnetic circuit.

In series with brushes 27 and 28 is a reactance coil 34, and in series with brushes 29 and 30 is a reactance coil 35, these coils being joined in parallel with a conductor 36 which forms a part of the external D C circuit. Coils 34—35 are wound upon a common core which is constructed to have a closed magnetic circuit.

The coils 31, 32, 34 and 35 are of equal number of turns and of the same size of wire and when arranged as shown and described, the current flowing through the respective circuits in which the coils are located, will be equalized. If there is a tendency for a greater current to flow through one circuit than the others, the equilibrium of the magnetic field is disturbed and reaction upon each of the fields set up by each of the coils chokes the current flowing in the particular circuit tending to carry excess current, and it finds a more ready path through the other circuits, and so the equality is preserved. Therefore each of the brushes with which the circuits 31, 32, 34 and 35 are connected will let through substantially equal amounts of current and will eliminate the sparking incident to unequal amounts of current being carried by the various brushes.

These reactances perform another function, at least those upon the opposite side of the D C line do, in that they prevent current flowing outward from the battery during the time that the voltage from the machine is less than the voltage of the battery.

In connection with a machine of this type, I use condensers which are so arranged and joined in the circuit that a condenser is always in parallel with the break upon both sides of the circuit, as the rotatable bodies which carry the conducting portions are caused to turn. These condensers are arranged in two groups represented at 37 and 38, one group of condensers being connected in parallel with the line in which the reactance coil 32 is situated, and also connected with the line with which the reactance 35 is in series, and the intermediate points upon opposite sides of the condenser circuit are connected with the sides of the alternating current. The condenser group 38 is connected at one point with the circuit containing the reactance 31, and at the opposite point with the circuit containing the reactance 34, and the opposite intermediate points upon the condenser circuit are also joined with the alternating current circuit. The manner in which these condensers are connected is fully explained in a patent granted to me on December 24, 1912, No. 1,048,034, and their function in their present situation is the same as that explained in that patent.

In many instances it is desirable to use a number of brushes bearing on a single segmented body, in place of using a single brush, this for the purpose of increasing the current carrying capacity of the machine.

In Fig. 5, I have shown such an arrangement, as is shown in Fig. 4, with the exception that in place of the single brushes 24,

28, 26 and 30, and brushes 23, 27, 25 and 29, there are two brushes which are designated at 24^a, 24^b 28^a, 28^b, 26^a, 26^b, 30^a, 30^b, and 23^a, 23^{a1}, 27^a, 27^{a1}, 25^a, 25^{a1}, 29^a, 29^{a1}.

5 For purposes of description, we may assume that the brushes 23^a, 23^{a1}, 24^a and 24^b, and the brushes 25^a, 25^{a1}, 26^a and 26^b, are electrically connected with the positive side of the D C circuit, while brushes 27^a, 27^{a1}, 10 28^a, 28^b, and brushes 29^a, 29^{a1}, 30^a, 30^b, are connected with the negative side of the D C circuit. The groups of segments with which 15 these brushes respectively coöperate, are electrically connected with each other, and with the A C circuit, in the same manner as is shown in Fig. 4.

The brush 24^b and brush 23^{a1} are connected with the reactance coil 24^a; the brush 24^a and brush 23^a are connected with the 20 reactance coil 24^c and so on throughout the brushes which are connected with the positive side of the line. The brush 29^a and brush 30^a are connected with the reactance 25 29^c, while the brushes 30^b and 29^{a1} are connected with the reactance coil 29^d, and so on throughout the brushes connected with the negative side of the D C circuit.

It will thus be seen that all of the brushes are individually connected with the D C 30 circuit, through a reactance and these reactances are so proportioned that each will let through an equal amount of current. Therefore the total current flowing will be substantially equally proportioned between 35 the brushes, because of the readier path afforded for the current.

It will be apparent that more than two brushes may be used in each set, if desired.

As explained with respect to the machine 40 indicated in the diagram of Fig. 4, I use condensers, the function of the condensers being the same as that explained with respect to Fig. 4, and there is inserted a group of condensers between each brush and coil connection upon the positive side of the D C line, and a corresponding brush connected with the negative side of the D C line, and this group of condensers will also be connected with the alternating current circuit.

50 Explanation of one group of condensers, it is believed will suffice for all. The group of condensers 37^a will be connected at diametrically opposite points with the connection between the brushes 23^{a1}, 24^b and the reactance coil 24^a and with the connection between the reactance coil 28^c and the brushes 27^{a1}, 28^b. The intermediate diagonally opposite points of the condenser group will be connected with the two sides 55 of the A C circuit.

I do not limit my invention to use in connection with the herein described machine, as it will be apparent that its use may be of wider application.

Having described my invention, what I claim is:

1. The combination with a device for producing a pulsating current, having a plurality of positive and negative terminals, and a reactance coil connected in series with each terminal, a common core upon which said coils are wound, the reactance coils for the positive terminals being connected in parallel with each other, and the reactance coils for the negative terminals being connected in parallel with each other.

2. The combination with an A C and D C circuit, of a device adapted to connect the sides of one of said circuits alternately with the sides of the other circuit, said device 80 having a plurality of positive and negative terminals, a reactance coil connected in series with each of the terminals, a common core upon which said coils are wound, the reactance coils for the positive terminals being connected with each other in parallel, and the reactance coils for the negative terminals being connected with each other in 85 parallel.

3. The combination with an A C and D C 90 circuit, of a device adapted to connect the sides of one of said circuits alternately with the sides of the other circuit, said device being provided with a plurality of positive and negative terminals, a reactance coil 95 connected in series with each of the terminals, a common core upon which said coils are wound, the reactance coils for positive terminals being connected with each other in parallel, and the reactance coils for negative terminals being connected with each other in parallel, and a circuit containing 100 capacity adapted to be inserted between the sides of the A C circuit and each pair of positive and negative terminals of said device.

4. The combination with a device for converting alternating current to direct current, the said device being provided with a plurality of direct current positive terminals, and a plurality of direct current negative terminals, and a reactance coil connected in series with each of the positive and negative terminals, a common core upon which the coils are wound, the reactance coils for the positive terminals being connected in parallel with each other, and the reactance coils for the negative terminals being connected also in parallel with each other.

5. The combination with A C and D C 110 circuits, of a device adapted to convert the alternating current to the direct current, said device being provided with a plurality of direct current positive terminals, and a plurality of direct current negative terminals, a reactance coil connected in series 125 with each of the said terminals, a common

core upon which the coils are wound, the reactance coils connected with the positive side of the D C circuit, and the reactance coils connected with the negative terminals,
5 being connected in parallel with the negative side of the D C circuit.

In testimony whereof, I hereunto affix my signature in the presence of two witnesses.

ARTHUR R. BULLOCK.
